UNITED STATES PATENT OFFICE.

CHARLES F. KURZ, OF CLEVELAND, OHIO.

DESIGN FOR A PRESCRIPTION-CASE.

40,700.

Specification for Design.

Patented May 17, 1910.

Application filed January 12, 1910. Serial No. 537,794. Term of patent 7 years.

To all whom it may concern:

Be it known that I, CHARLES F. KURZ, a citizen of the United States of America, residing at Cleveland, in the county of Cuyahoga and State of Ohio, have invented a new, original, and ornamental Design for Prescription-Cases, of which the following is a specification, reference being had to the accompanying drawing, forming part thereof.

The accompanying drawing is a front view in perspective of a prescription-case embodying my ornamental design.

I claim:

The ornamental design for a prescription-case as shown.

CHARLES F. KURZ.
